UNITED STATES PATENT OFFICE.

FRANK B. HINE, OF EL PASO, TEXAS.

TAG-FASTENER.

1,175,760.

Specification of Letters Patent. Patented Mar. 14, 1916.

Application filed August 15, 1913. Serial No. 784,981.

To all whom it may concern:

Be it known that I, FRANK B. HINE, a citizen of the United States, residing at El Paso, in the county of El Paso and State 5 of Texas, have invented new and useful Improvements in Tag-Fasteners, of which the following is a specification.

An object of the invention is to provide a device for attaching tags to packages 10 wrapped by twine or cord.

The invention embodies, among other features, the provision of a simple device for use in attaching tags to the cord of a package.

15 The invention further embodies a device which is preferably made of a single piece of wire-like material and which can be cheaply manufactured and readily applied to the cord of the package.

20 In the further disclosure of the invention reference is to be had to the accompanying drawings, constituting a part of this specification, in which similar characters of reference denote corresponding parts in all the 25 views, and in which:

Figure 1 is a perspective view of a package showing my device applied thereto; Fig. 2 is a fragmentary side elevation showing the first step in attaching the device to the 30 cord; and Fig. 3 is a similar view showing the device applied to the cord.

Referring more particularly to the views, I provide a fastener 10 consisting of a single piece of wire-like material 11 bent intermediate its ends to form a loop-like holder 12 adapted to support a tag 13, the ends of the piece of material 11 being bent in the form of hooks 14 relatively spaced apart and having their extremities extending toward the body 40 of the piece of material but slightly spaced therefrom, with the said hooks inclined with respect to the body of the piece of material, as shown in the views.

In applying my device to the cord 15 of a package 16, the cord is first received in one 45 of the hooks to pass therethrough and the fastener is then manipulated so that two portions of the cord will pass through the second hook as shown in Fig. 2. The fastener is then manipulated so that another 50 portion of the cord will be received within the first hook and will cross the portion of the cord initially passed through the second hook, thus securely attaching the fastener to the package and preventing the 55 same from sliding on the cord.

It will be understood that in applying the fastener to the package any slack in the cord will be taken up on account of twisting the fastener around the cord and thereby my 60 device not only acts as a tag fastener but also aids in more securely holding the cord to the package.

Having thus described my invention, I 65 claim:

A tag holder comprising a wire bent to form a loop having converging sides, sections of said wire adjacent its ends being bent outwardly at right angles to the loop body in opposite directions, the ends of the 70 wire being bent inwardly toward each other and overlying in spaced relation the outwardly extending sections to provide cord receiving loops whereby the holder may be connected with a cord to prevent lateral 75 movement of the holder along the cord, and extensions formed from said ends, and contacting with and extending beyond the respective converging sides of the loop interiorly thereof.

In testimony whereof I affix my signature in presence of two witnesses.

FRANK B. HINE.
